STOVE OR RANGE

Carl H. Hoffstetter and Robert F. Hoffstetter,
Erie, Pa.

Application October 19, 1938, Serial No. 235,902

5 Claims. (Cl. 126—214)

Our invention relates to stoves and ranges and more particularly to that type of stoves and ranges having spaced or divided cooking tops, as illustrated in our Design Patents Nos. 67,549 and 5 102,430.

The object of our invention is to provide a service drawer or tray in the cooking top of the range which does not interfere with free use of the working surface between the top burners.

10 Other objects and advantages of the invention will be understood as the description is considered in connection with the accompanying drawing, in which:

15 Figure 1 is a top perspective view of a stove, partly broken away, embodying our improved service drawer or tray; and

Figure 2 is a side view of the same partly in section.

Referring more particularly to the drawing 1 20 denotes a range provided with broiling and baking ovens 2 and 3, the front openings of which are normally closed by doors 4 and 5 respectively. There are two burner compartments 6 and 7, adjacent opposite ends of the range, for housing 25 suitable gas or other burners, not shown. The enameled sheet metal portions 8 and 9 of the range top 10, provide working surfaces extending between the side walls 11 of the range and the top openings 12 and 13 of the burner compartments 6 and 7. The parts 8 and 9 also function to prevent pots or pans etc. from being accidentally pushed off the burners to the floor.

When the burners are not in use, the openings 12 and 13 may be closed by porcelain enameled 35 sheet metal covers 14 and 15, suitably hinged at their rear ends to the stove top. These covers thus afford relatively wide working surfaces, for supporting dishes, pans and the like.

Arranged between the burner compartments 6 and 7 is an intermediate well or compartment 16, in which a sheet metal drawer or box 17, is snugly housed. This box is designed to contain knives, forks, spoons or other utensils used in cooking operations. A hinged sheet metal enameled cover 18 normally closes the well 16 and hides the box 17 from view. Access may be readily had to the box 17 by raising the cover 18 to expose the box to view. When in closed position the top face of cover 18 is flush with table top portions 8 and 50 9 and substantially flush with the burner grids 19, thus also affording additional working surface. It will be noted that the additional working surface thus provided is most conveniently positioned with respect to the burner grids. In fact cooking 55 utensils may be conveniently slid or lifted from

one to the other, and the same is true of the covers 14 and 15 when the latter are in closed position.

The cover 18 is sustained in elevated position and against accidental closing by means of a wire ball 20, the offset ends 22 of the arms 23 and 24 of which are pivotally mounted in the oppositely disposed side walls of the well 16. One offset end 22 of the ball 20, is extended and curved to form a crank arm 25 to which one end of a coil spring 10 26 is connected, the other end of the spring being attached to the back of the stove. Normally this ball lies in an out of the way position within the box 17, as indicated in dotted lines in Figure 15 2. When the user of the range is cooking and desires to use knives, forks, spoons or other articles kept in receptacle 17, she simply lifts the cover 18 to a substantially vertical open position with one hand and with the other swings the ball upwardly from an off center position, whereupon the spring 26 pulls the ball into contact with a pair of lugs 27, spot welded or otherwise suitably secured to the lift cover. These lugs act as a stop for the wire ball when it springs back into position for sustaining the cover in a slightly 25 forwardly inclined position. The spring pressure of the ball against the stops offers frictional resistance to further upward or opening movement of the cover which might result in damage to the cover or its hinges.

In order to close the cover 18 it is merely necessary for the housewife to swing the ball forwardly and downwardly upon its pivots to a below dead center position within the box 17, where it will not interfere with the cover as the latter 35 moves by gravity or is manually moved to horizontal or closed position.

Having thus described our invention, what we claim is:

1. A range having a utensil compartment beneath the range top and accessible through said top, a hinged cover for said top movable from a closed horizontal position to a substantially vertical open position, a ball hingedly mounted in said utensil compartment for movement out of 40 said utensil compartment into engagement with said cover for sustaining said cover in open position.

2. A range having a utensil compartment beneath the range top and accessible through said top, a hinged cover for said top movable from a closed horizontal position to a substantially vertical open position, means hingedly mounted in 50 said utensil compartment for movement out of said utensil compartment independently of the 55

movement of the cover and into engagement with said cover for sustaining said cover in open position.

3. A range having a utensil chamber opening 5 through the top of the range, a hinged cover for said utensil chamber, a spring actuated bail pivotally mounted in said utensil chamber and movable out of said utensil chamber for sustaining the cover in partially open position and movable into 10 said utensil chamber when not in use, and a stop member adjacent the rear end of said cover against which said bail rests and opposes movement of said cover to completely open position.

4. A range having a compartment opening 15 through the top of the range, a hinged cover for said compartment movable from horizontal to vertical position to open said chamber, a bail

pivotedly supported at its ends in said chamber and normally housed within said chamber, a stop member on the under face of said cover adjacent the rear end thereof and spring means for swinging said bail upwardly into engagement with said cover and for forcing said bail frictionally against said stop to sustain and maintain said cover in substantially vertical position. 5

5. A range having a utensil chamber opening 10 through the top of the range, a sheet metal cover therefor, means for supporting said cover in open position, and said means being movable into said utensil chamber independently of the movement of the door when not in use. 10
